UNITED STATES PATENT OFFICE.

CHARLES B. GALVIN, OF NEW YORK, N. Y.

PROTRACTOR.

Application filed October 24, 1923. Serial No. 670,601.

This invention relates to a new and improved protractor, and has for an object the provision of a protractor whereby improved utility and accuracy for coordinating, plotting and measuring angles may be achieved.

Another object concerns the provision of means whereby by reason of the application of well known geometrical laws the scale of graduations on a protractor is doubled so that the readings on the scale are thereby caused to be much more accurate.

A further object concerns the provision of two slides on the protractor which can relatively be adjusted and manipulated to perform various other useful functions.

The invention is illustrated in the drawings, of which—

Figure 1 is a plan view of the protractor;

Fig. 2 is a section taken on the line 2—2 of Fig. 1; and

Fig. 3 is a section taken on the line 3—3 of Fig. 1.

The form of the invention shown in the drawings is a preferred form, although it is understood that modifications in the construction and arrangement of the parts and in the character of the materials used may be adopted without departing from the spirit of the invention as set forth in the appended claims.

The basic characteristics of this instrument depend upon the application of two geometrical laws, the first of which is that any angle inscribed in a circle is equal to half the angle subtended at the center; the other law is that any angle inscribed in a semicircle is a right angle.

The preferred form of my invention as shown in the drawings comprises a ring 1 of any suitable material provided with graduations 2 along its outer periphery. This ring is provided with a crossbar 3 the edge 4 of which is in line with the diameter of the ring, and is provided with a center line 5 intersecting the edge 4 at the center of the circle of graduations. The ring at one side is provided with a diametrical line 6 along which a plotting aperture 7 is disposed. This aperture is provided to permit a marker point to be inserted therein to mark on materials beneath the protractor.

The ring is provided with an outwardly extending annular flange 8 which, as shown in Fig. 2, is slightly tapered. The ring is also provided with an outwardly extending arm 9 which extends outwardly from the

ring on the side opposite that on which the aperture 7 is disposed. This arm on its outer edge is provided with a plate 9^a having an aperture in which a set screw 9^b is disposed to permit the plate to be clamped in any desired position on the arm 9. This plate is provided with an aperture 10 representing the position of a point a definite distance from the center 5. On this plate are two other index points 11 and 12 disposed at definite distances from the center 5. The plate 9^a is adjustable to aline the index points 10, 11 and 12 with the diameter of the circle represented by the edge 4 of the crossbar 3.

The protractor is provided with a pair of arms 13 and 13^a extending outwardly from the ring in radial directions therefrom. The arm 13 on its inner end is provided with plates 14 and 15 lying on opposite sides of the flange 8 and adjustably engageable therewith by means of a screw 10' so that the flange can be gripped by these plates to hold the arm 13 on the flange in its rotative movement around the center 5. The arm is provided with a straight edge 13^b in line with the radius of the circle of which the center is represented by the numeral 5.

On the outer end of the arm there is fastened a plate 17 adjustable by reason of the slot and set screw 18 in a manner similar to the adjustment of the plate 9^a on the arm 9. On this plate are disposed indicating points 21 and 22 as well as an aperture 19 having an apertured plate 20 therein, the aperture in the plate 20 representing a point a distance from the center 5 equal to the distance of the point 10 therefrom. The index point 21 is equidistant from the center 5 with the index point 11, and the index point 22 is equidistant with the index point 12 from the center 5. The rotatable arm 13 is associated in its operation with a pair of plates 24 and 25 which are disposed on opposite sides of the flange 8 adjacent the arm 13 and are held together on said flange by the clamping screw 26. The upper plate 24 of the pair of plates is provided with an apertured stud 27 through which a shaft 29 passes. The other end of this shaft is engageable with a stud 28 on the plate 14.

A thumbpiece 30 formed on the end of the shaft 29 permits it to be rotated. This shaft is threaded into the stud 27, and a spring 31 embraces the shaft 29 between the studs 27 and 28. By rotating the shaft 29, after

having clamped the plates 24 and 25 firmly in a fixed position on the flange 8, the position of the arm 13 can be varied very accurately and by very small degrees with respect to the scale on the ring 1. It is, of course, understood that the arm 13 is provided with a vernier scale 20^a, so that after the plates 24 and 25 have been clamped to the flange 8 the manipulation of the shaft 10 29 will permit the vernier to be properly set and read in the usual manner.

It will be observed that the arm 13^a is of a construction identical with that of arm 13, the parts of this construction being numbered with the same numerals as corresponding parts on the arm 13 with the suffix "a" after them. The operation and manipulation of this arm is identical with the operation and manipulation of the arm 13.

20 It will be observed that the scales on the ring 1 extend from a zero point adjacent the aperture 7 in either direction around the ring and that each half of the ring is divided into 90°. By reason of the fact that each 25 arm rotates around the center 5, we will assume that the arm 13, for instance, is positioned opposite the numeral 30 on the upper scale. In accordance with the fact that the numeral 30 is laid off to represent an angle 30 of 30°, this angle is formed between lines drawn, for instance, from the aperture 20 to the aperture 10 and then drawn from the aperture 10 to the aperture 7. This angle is 30°, whereas the angle drawn between the 35 aperture 20 and the center 5 and the aperture 7 is actually 60°, in other words, twice the previously mentioned angle. However, by being able to divide up the scale from zero to the 30° mark into thirty spaces instead of sixty, I am able to set the slide of the rotatable arms with much greater accuracy.

It is to be understood, of course, that the angles can be read by considering either the 45 apertures 20, 10 and 7 or by considering the apertures 20, 10 and 20^b. Whereas, on the other hand, the apertures 21, 11 and 21^a can be considered as those apertures through which lines are to be drawn to lay off the 50 angle. It may, further, be desirable to use the outside index points 12 and 22^a together with the aperture 7.

Therefore, the reading of either one of the verniers is the measuring of the angle 55 formed by lines drawn from one of the index points on said vernier apparatus to the corresponding index point on the arm 9 and thence to the aperture 7, which angle is the angle inscribed in the semicircle and is half 60 the angle subtended at the center of the circle by the same arc. By reason of this application of the geometrical laws above mentioned, a geometrical magnification is obtained in laying off the angle by reason of 65 the fact that the diameter of the circle in-

stead of the radius is available for a base. Furthermore, an increased degree of refinement in the reading or setting of the vernier is obtained, because of the fact that the intercepted angle is measured by twice the 70 subtended arc.

It is, of course, understood that by setting one of the verniers at zero a triangle formed between an index point on this vernier and corresponding index points on the other vernier and the arm 9 will always be a right angle triangle because this triangle is inscribed in a semicircle of which the diameter of the protractor between two index points is the diameter of the circle.

This device is, furthermore, useful for dropping perpendiculars, because while one vernier may be set at zero, the other forms a right angle. The movable one may, therefore be moved to any convenient position 85 and then clamped.

It will, therefore, be observed that I have provided a simple and efficient device for the purpose of readily plotting angles and directions. The scales used are so related to 90 well known geometrical laws that the accuracy of the readings is increased two fold. The relation between the movable verniers and the diametrical base line of the protractor is such that by setting them as above designated a right angle can be formed in a variety of convenient places by the movement of one of the verniers while the other is set.

It is, furthermore, to be noted that the 100 latitude and departure of a course may be scaled directly as follows: With the lower vernier set on zero and the upper vernier set on a given bearing, and with the crossbar 3 set on a course, scale off to any convenient scale 105 one-half the length of the course on each side of the center of the crossbar; also measure off this distance from the center along the radius leading from the center through the upper branch. The scale distance from the last-mentioned point to the above-mentioned points on the diameter will then equal the latitude and departure, respectively. This is true for the reason that the relation of the verniers 1, such as described, constitutes a right angle triangle, and the relation of the three points mentioned constitutes a right angle triangle.

What I claim is:—

1. A protractor which comprises a ring 120 having a diametrical crossbar and a fixed arm extending radially outward at one end of said crossbar, there being an index point on said arm, an arm mounted on said ring to rotate about the center thereof and having an index point thereon at the same distance from the center of said ring as the previously mentioned index point.

2. A protractor which comprises a ring, a diametrical cross bar secured to the ring, 130

a fixed arm extending radially outward from one end of said crossbar, there being an index point on said arm, a pair of arms mounted on said ring to rotate about the center 5 thereof and adapted to rotate in opposite directions from the opposite end of said diameter, each of said arms having an index point thereon at a distance from the center of said ring equal to the distance from the 10 center of the first-mentioned index point on the fixed arm.

3. A protractor which comprises a ring provided with a plurality of graduations thereon, the values of said graduations being 15 given in terms of half the angles subtended at the center, a diametrical crossbar secured to the ring, a fixed arm extending radially outward from one end of said crossbar, a pair of arms mounted on said ring to rotate 20 about the center thereof, there being a plu-

rality of index points on each of said arms, each index point being at a distance from the center of said ring equal to a respective index point on the other arm.

4. A protractor comprising a ring having 25 scale graduations extending in opposite directions from the zero point, a diametrical crossbar secured to the ring, said point located at one end of said crossbar, a fixed arm extending radially outward from the 30 ring at the opposite end of said diameter, an arm mounted on said ring to rotate about the center thereof, there being index points on both of said arms at equal distances from the center of said ring, the graduations on 35 said ring having values which are given in terms of half the angle subtended at the center.

CHARLES B. GALVIN.
